RACK FOR MAGAZINES AND THE LIKE

Fred D. Farr, Mamaroneck, N. Y., assignor to
Revere Copper and Brass Incorporated, Rome,
N. Y., a corporation of Maryland

Application April 28, 1936, Serial No. 76,783

1 Claim. (Cl. 211—43)

My invention relates to a support or rack for magazines and other articles of similar shape, and will be best understood from the following description when read in the light of the accompanying drawings of an embodiment of the invention, while the scope of the invention will be more particularly pointed out in the appended claim.

In the drawings:

10 Fig. 1 is a side elevation of the rack constructed according to the invention;

Fig. 2 is an end elevation of the rack according to Fig. 1 with parts broken away; and

Fig. 3 is a section on the line 3—3 of Fig. 1 with parts broken away.

Referring to Figs. 1, 2 and 3 of the drawings, the rack illustrated comprises a base 1 formed of a flat sheet of metal opposite ends of which are bent to form tubular-like portions 3. At opposite ends of these tubular portions are spheres 5 of greater diameter than said tubular portions, these spheres being held firmly against said ends by rods 7 the ends of which are screw-threaded into tapped holes formed in the spheres, as indicated at 9. In this construction the spheres are adapted to rest upon a supporting surface as, for example, the flat top of a table.

Extending upwardly from the center portion 30 of the base of the rack is a vertically positioned, flat, tubular member 11 opposite sides 13 of which form abutments against which the flat sides of magazines M are adapted to rest.

As shown, the upwardly extending tubular member 11 at its upper end carries a member 15, which may be of molded composition material, having an opening 17 through which the fingers may be inserted, thus facilitating use of the member as a handle grip. As illustrated, the member 15 is flat, having a thickness approximately the width of the narrow interior dimension of the tubular member 11, enabling the upper end of the tubular member to be cut away, as illustrated in Fig. 2, to provide at opposite 45 sides of the member 15 projecting lugs 19 secured to the member 15 by rivets 21.

At opposite sides of the upwardly extending tubular member 11 are spring members S formed of flat, resilient sheet metal of uniform thickness. As shown, each of these members is bent or coiled to provide an upwardly extending portion 23 which is outwardly bowed relative to the adjacent side 13 of the member 11, and to provide a free terminal portion which presents a 55 convex surface 25 adapted to contact with the

flat side of a magazine and hold it against the adjacent side 13 of the member 11. The lower ends of the spring members are fixed to the base by screws 27 and 29, thus enabling the spring members to uncoil to permit insertion of magazines between them and the member 11. This uncoiling tends to occur mostly at the portions of greatest radius of curvature, that is to say, at the inclined portions of the spring members which extend upwardly from the base to roughly the point where they begin to turn toward the member 11, and to accentuate this effect the spring members, as illustrated, are tapered longitudinally, being of narrowest width adjacent the base. As indicated in Fig. 1, the magazines 15 rest upon the lower portions of the spring members and, for reinforcing these portions, beneath them are positioned relatively narrow, flexible reinforcing springs 31 of sheet metal which also are fixed to the base by the screws 29.

As illustrated, the springs 31 at opposite sides of the member 11 are integral, while the coiled spring members S are formed of separate pieces of metal. The tubular member 11 at its lower end receives a block 33 secured thereto by rivets 35, the screws 29 being tapped into this block and extending through perforations in the members S and 31 so that the screws 29 act not only to secure these members to the base but to secure thereto the tubular member 11. The screws 27 extend through perforations in the spring members S and are tapped into the base.

It will be observed that in the rack described means is provided which presents a base adapted to rest upon a supporting surface, also a pair of spaced abutments above the base against which the flat side of a magazine is adapted to rest, the spacing of these abutments being less than the width of the base so as to make a compact device.

It will be understood that within the scope of the appended claim wide deviations may be made from the forms of the invention illustrated and described without departing from the spirit of the invention.

I claim:

A rack for magazines and the like having, in combination, vertically extending means opposite sides of which form an abutment against which the sides of magazines are adapted to rest, a flat elongated strip of flexible spring material at each side of said vertically extending means coiled to present a scroll and having an end in fixed relation to said means, each scroll having a flexible upwardly and outwardly bowed portion 55

extending outwardly from adjacent the abutment formed by said means providing an extensible support portion upon which the edges of magazines are adapted to rest and having a free portion opposed to said means for engaging the sides of magazines resting upon said extensible portion and holding them against said means, and a supporting base for said rack carrying said

scrolls and said means, the upper surface of said base beneath said scrolls being upwardly inclined away from said means and being adapted to support said extensible portions of said scrolls upon downward flexure thereof when weighted by the magazines. 5

FRED D. FARR.
